US0D1101492S

(12) **United States Design Patent** (10) **Patent No.:** **US D1,101,492 S**
(45) **Date of Patent:** **** Nov. 11, 2025**

(54) **SQUEEZE BOTTLE**

(71) Applicant: **Hydrojug, Inc.**, Ogden, UT (US)

(72) Inventors: **Hayden Wadsworth**, Ogden, UT (US);
Ethan Powell, Salt Lake City, UT (US);
Ryan Holmes, West Haven, UT (US)

(73) Assignee: **HYDROJUG, INC.**, Ogden, UT (US)

(**) Term: **15 Years**

(21) Appl. No.: **29/941,041**

(22) Filed: **May 7, 2024**

(51) LOC (15) Cl. **07-01**

(52) U.S. Cl.

(57) **CLAIM**

The ornamental design for a squeeze bottle as shown and described.

DESCRIPTION

FIG. 1 is a top perspective view of the squeeze bottle design;
FIG. 2 is a bottom perspective view thereof;
FIG. 3 is a first side view thereof;
FIG. 4 is a second side view thereof;
FIG. 5 is a third side view thereof;
FIG. 6 is a fourth side thereof;
FIG. 7 is a top view thereof;
FIG. 8 is a bottom view thereof; and,
FIG. 9 is a top perspective view thereof in an alternate position of use.
The dashed lines depict portions of the squeeze bottle that form no part of the claimed design.

1 Claim, 9 Drawing Sheets
